US0D1065702S

(12) **United States Design Patent** (10) **Patent No.:** **US D1,065,702 S**
(45) **Date of Patent:** **** Mar. 4, 2025**

(54) **PET CAGE FRAME**

(71) Applicant: **GUANGZHOU SAIR INDUSTRIAL CO., LTD**, Guangzhou (CN)

(72) Inventor: **Jiye Guo**, Guangzhou (CN)

(73) Assignee: **Guangzhou Sair Industrial Co., LTD**, Guangzhou (CN)

(**) Term: **15 Years**

(21) Appl. No.: **29/857,801**

(22) Filed: **Oct. 26, 2022**

(30) **Foreign Application Priority Data**

Aug. 25, 2022 (CN) 202230558177.9

(51) **LOC (15) Cl.** **30-02**

(52) **U.S. Cl.**

USPC **D30/115**

(58) **Field of Classification Search**
